FIRE WALL CONSTRUCTION

George Crombie, Sr., Denver, Colo., assignor to
 The Stearns-Roger Manufacturing Company,
 Denver, Colo.

Application February 12, 1936, Serial No. 63,581

12 Claims. (Cl. 72—101)

My invention relates to fire wall construction, and more particularly to that type of construction in which an inner expansible fire wall is anchored to an outer cover wall and its supporting structure.

In the construction of boiler settings and the like, difficulties are encountered in anchoring the component parts of the structure due to the fact that the inner fire wall is subjected to temperature variations of such magnitude that the material composing the wall is subjected to a wide range of expansion and contraction.

Various constructions and devices are now in use for anchoring a fire wall of this type to an outer wall. The chief difficulty with the means now available for this purpose is that costly parts and fastening devices are employed, with the result that in constructing a wall of a given size, of this character, the cost of materials used is much greater than the cost of materials which could be used if such fastenings were not employed.

In addition to the foregoing, where special fastenings and brick construction are used, additional time is required in fixing the same in position in the wall, with the result that in a wall of this type, of any given size, the labor cost for building the same is materially increased.

It is an object of the present invention to provide a fire wall construction which is effective in anchoring the inner fire wall to an outer wall, free for the required amount of expansion, and which can be constructed at practically the same cost as a fire wall in which fastening devices have been omitted.

Another object of the invention resides in the provision of a special tile construction effective for positively holding special castings, when in place in a wall.

A further object of the invention is the provision of a special casting to be anchored in a fire wall, which is so constructed as to permit a circulation of air about its entire surface when in place in a fire wall, to prevent excessive heating of the same, and which cooperates with a fastening device anchored in a cover wall to effectively maintain the said walls in substantially uniform spaced relation while permitting a free up-and-down and lengthwise movement of either wall, by expansion and contraction produced by temperatures to which the wall is subjected.

Still another object of the invention resides in a novel fire wall construction by which an inner fire wall is positively anchored to an outer cover wall, and which is easily built and durable in use.

A still further object of the invention is the

provision of a combined supporting and anchoring device which is slidably attached to the columns or beams supporting an outer cover wall.

Still other objects reside in novel steps and treatments, and novel combinations and arrangements of parts as will more fully appear in the course of the following description. To give a better understanding of the invention, reference is made to the accompanying drawings in the several views of which like parts have been similarly designated, and in which

Figure 1 represents a perspective view of a portion of a boiler setting or the like, to which my invention has been applied;

Figure 2 is an end elevation of a wall embodying the construction illustrated in Figure 1, and showing the manner of applying the fastening devices to the walls in section;

Figure 3 is a perspective view of the tile construction used for anchoring the fastening devices in the fire wall;

Figure 4 is a plan view of the casting used in connection with the tile of Figure 3;

Figure 5 is a section taken along line 5—5, Figure 4;

Figure 6 is a fragmentary perspective view of a portion of a boiler setting or the like, employing an insulated metal cover wall, and having combined anchoring and supporting elements connecting the inner fire wall with the supporting beams of the metal wall;

Figure 7 is a fragmentary vertical section through a wall similar to the wall of Figure 6, illustrating the manner of applying the fastening devices, and corresponding in position to the lines 7—7 of Figure 8;

Figure 8 is a section taken along line 8—8, Figure 7;

Figure 9 is a fragmentary perspective view of another embodiment for anchoring the cover wall of Figure 1 at the corners;

Figure 10 is a fragmentary plan view of an expansion joint used in the present construction; and

Figure 11 is a plan view of another embodiment of a casting used in the wall construction illustrated in Figure 6.

Referring first to Figure 1, the reference numeral 12 designates an inner fire wall constructed of suitable materials such as fire brick, or the like. Adjacent and in spaced relation to the fire wall is an outer cover wall 13 constructed of ordinary brick. At various intervals along the length of wall 13, structural members in the form of anchoring columns 14 are located.

In Figure 1 the column 14 has been illustrated in the form of an I-beam of structural steel acting as the corner support for the wall. While no anchoring has been shown for the beam 14, it will be understood that it is fixedly anchored by setting in cement or in otherwise fastening it to the structure in which the boiler setting is being built.

At selective elevations above a floor 15 or other base on which the structure is supported, brace beams 16 are built into the wall 13. These beams are preferably of the usual structural steel angle iron construction of L-section, and are disposed with one flat side between courses of the brick wall 13, and with the other side of the beam flush with the outer face of the wall 13. The faces of the members 16 disposed between the courses of brick are provided at selective intervals with lengthwise extending slots 17.

20 The I-beams 14 which serve as the corner supports for wall 13 are provided on the outer face of the innermost flange with an angle iron section 18 suitably fastened thereto as by welding, riveting or the like. The wall 13 is built against and in alignment with the face of the angle section projecting outwardly from the flange of I-beam 14. Hook members 19, in the form of flat metal bars having an offset extension, are suitably fastened on the outer face of beam 16 adjacent the angle irons 18, with the extension portion of the same overlapping and bearing against the projecting section of the angle iron 18.

From the foregoing, it will be apparent that 35 the wall 13 will at all times be held against angle iron 18, in alignment with the projecting portion of the same, while being free for lengthwise movement as the fastening hook 19 is free for lengthwise movement relative to the section of angle iron 18, which it bears against. It is also apparent that the fastening 19 and wall 13 are free to slide along this section in an up-and-down direction.

The wall 12, at the same elevation as the beams 45 16, has a course of refractory tile 20 in place of the usual fire brick of the wall. This tile course consists of two complementary sections 20a and 20b, each provided at one end with a specially shaped recess 21, whose function will be explained hereinafter. These tile sections are preferably of the same length as the fire brick, but of greater width, and of a thickness approximating the thickness of a usual fire brick.

When placed in the wall, the sections 20a and 55 20b are disposed with the recesses 21 in adjoining relation, and are fixed in position by applying mortar or cement between the adjoining faces.

Castings 22, preferably formed of a metal or 60 alloy possessing heat-resisting properties, such as cast iron, are fitted in the recesses 21 at the time the sections 20a and 20b are installed in the wall.

The recesses 21 comprise an inner rectangular section 23, and a narrowed entrance portion 24, 65 extending to the outer end of the block centrally thereof.

A casting 22 comprises two widened ends 25, and 70 26 respectively, connected by a narrower neck 27. The end portion 25 and neck 27 are shaped in conformity with the sections 23 and 24 respectively, of recess 21, and are of a dimension permitting them to snugly fit in the said recessed portions. The outer end of the portion 25 is re- 75 cessed as indicated at 28, and the portion 25 and

neck 27 are of channel section which is clearly shown in Figure 5.

When the casting 22 is fitted in the adjoining recesses 21 of the blocks 20a and 20b, air from the space 29 between the walls 12 and 13 is free 5 to circulate across the upper and lower faces of the portions 25 and 27, and across the recessed end 28 of portion 25.

The other end portion 26 of casting 22 is provided with a slot 30, disposed transversely to the 10 lengthwise axis of neck 27. A tie bar 31 having upstanding tongues 31a and 31b at its ends, connects casting 22 with a beam 16. The tongue 31a is inserted through one of the slots 17 of the beam, and the tongue 31b projects upwardly 15 through the slot 30 in casting 22. Additional courses of brick are then built over the beam 16, and its adjoining brick course, with the result that the wall 13, beam 16 and tie 31 become a unitary structure.

Similarly, additional courses are built over the course of tile 20, and the wall 12, tile 20 and casting 22 also become a unitary structure. It will be observed that the slots 30 are of much greater length than the width of tongue 31b. While 25 Figure 1 shows the tile course as consisting of a row of adjoining tiles 20, it will be understood that if less anchoring is required, any selected number of fire bricks may be placed between two of the tiles 20.

30 It will be noted that in the wall construction illustrated in Figures 1 and 2, the bottom course of bricks in the wall 13 consists of a row of headers H on which six rows of stringers S are placed. Headers H are likewise placed immediately above and below the beam 16.

The practice is again repeated for the next rise of the wall, and so on. While the foregoing has been found to give excellent results, it will be understood that any arrangement of courses may 40 be employed and the fastening devices of the present invention utilized therewith.

The fire wall 12 is preferably started with a course of headers H and then alternate stringers S and headers H are used until the elevation for 45 tile 20 is reached. A row of headers H is preferably disposed above and below the tile course and the foregoing practice is also repeated for successive rises.

In certain types of wall construction, the 50 I-beams 14 will be replaced by an angle-iron column 14a (Figure 9) and the brace-beams 16 in this embodiment will be provided with slots 32 adjacent their ends. The angle-iron is apertured at 33 to receive a bolt 34, which extends 55 through the slot 32 and is fastened with a nut (not shown) or other suitable fastening. The slots permit lengthwise movement of beams 16 relative to angle-irons 14a and a limited up-and-down movement.

60 The wall construction illustrated in Figures 6, 7 and 8 is similar to the construction hereinabove described, and shows the application of the fastenings to a metal cover wall 35.

This wall consists of an outer cover plate 35a 65 of sheet metal or the like, and an inner cover plate 35b of the same or a similar material. The walls 35a and 35b are spaced to admit a layer of asbestos or other suitable refractory insulation 36 to be disposed therebetween.

70 The insulation 36 in wall 35 is effective in preventing the outer cover plate 35a from being subjected to the temperature variations encountered in the air space 29 between the outer wall 35 and the inner fire wall 12, and as a result, the plate 75

35a may be fastened to columns 14 by riveting, welding or in any other suitable manner.

The inner plate 35b is subjected to temperature variations through a wide range and to accommodate the resulting expansion and contraction, the plate 35b is preferably formed of a suitable expanded metal.

At intervals along wall 35, supporting columns 37 in the form of I-beams, suitably anchored at the base by any well-known method, are provided. The walls 35a and 35b are fastened in any suitable manner to the outer flange 37a and the inner flange 37b respectively of columns 37 intermediate the columns 14.

15 The fire wall 12 in Figures 6, 7 and 8 is constructed in the manner hereinbefore described with courses of tile 20 at selective elevations in the same.

In Figures 7 and 8, the wall anchors or fastenings are illustrated. A casting 22a similar to the casting 22 of Figure 4 is used to anchor the fire wall 12 to the cover wall 35. This casting consists of an anchor portion 25a, a narrowed neck 27a and a fastening portion 26a. The portion 25a is provided with a recess 28a similar to the recess 28 of casting 22, and the neck 27a is similar to the neck 27 of casting 22, except that it is of greater length. The channeled construction of portion 25a and neck 27a corresponds to the channeled construction of casting 22, but terminates intermediate the ends of neck 27a as shown in Figure 11.

The portion 26a has a T-shaped recess 38 extending inwardly from its outer end with the greatest width of the recess of a dimension sufficient to receive the flange 37b of column 37.

The columns 37 have their flanges 37b recessed at any selective elevation as indicated at 39 in Figure 7 to narrow the width of the flange sufficiently to permit the portion 26a of a casting 22a to be disposed with the inner boundary of recess 38 bearing against flange 37b, after which the casting may slide downwardly to the elevation of the tile course 20 with the portion 26a embracing the flange 37b.

The anchor portion 25a of casting 22a is then fitted in the complementary recesses 21 of tiles 20a and 20b.

If desired, this method of fastening may be used alone, and it will be readily apparent that the walls 12 and 35 will be held in fixedly spaced relation, while the wall 12 will be free for up and down movement relative to wall 35 by expansion and contraction.

The casting 22a fits flange 37b loosely enough to permit limited lateral movement, and also fits the recess 21 loosely enough to permit some additional lateral movement.

60 As a result of the foregoing, the fastening arrangement of this embodiment of the invention functions in all essentials in the same manner as the fastening devices illustrated in Figure 1.

The fastening device illustrated in Figure 6 may be used in conjunction with the casting 22a, or as the only fastening element for holding the wall 12 at a fixed distance from wall 35.

The device comprises a cantilever arch 40 provided at one end with an anchor portion 45 which is slotted as indicated at 41 in Figure 7. The opposite end of arch 40 bears a plate 42 projecting below the arch. The upper end 43 of plate 42 is widened and contains a T-shaped recess 44 extending inwardly from its outer end, with the

greatest width of the recess of a dimension sufficient to receive the flange 37b of column 37.

The fire wall 12 in the present construction has a course of tile 20 at a suitable elevation comprising complementary tile sections 20a and 20b, held in spaced relation by a plate 46 which extends beyond the outer face of wall 12 and terminates short of the inner face of the same. The space between the tiles 20a and 20b adjacent the inner face of wall 12 is filled with a suitable refractory insulation, such as asbestos, as indicated at 47.

The plate 46 is preferably of metal and is illustrated as being as long as the width of three of the tiles 20. The length of the plate may be varied to meet different requirements, and the tile may be built into a brick course, if desired.

The arch 40 is placed against flange 37b of the column, and the portion 43 is positioned in register with recess 39. The arch is next allowed to slide downwardly with the portion 43 embracing flange 37b, until the upper end of the arch is at the elevation of the tile course 20.

Plate 46 is then fitted in slot 41, the anchor portion 45 is fitted in recesses 21 and bolted to plate 46 as shown at 48.

The arch thus becomes effective in maintaining the spaced relation between walls 12 and 35, as well as providing a support for the portion of wall 12 resting on plate 46.

To limit any further downward movement of the arch, suitable bolts or rivets 49 are fastened in flange 37b to provide a stop in the path of plate 42.

In the case of high refractory walls subjected to intense heat, a considerable expansion and softening occurs under the load, and when the wall is cooled, this expansion is followed by a settling, which if repeated a number of times, frequently results in a collapse of the wall.

The arch 40 being freely slideable in an upward direction will accommodate any expansion to which the wall is subjected, but after the wall has cooled, the arch is only free to descend until the plate 42 engages the stops 49.

In Figure 10 an expansion joint for the corners of fire wall 12 has been illustrated. The fire brick are arranged in offset relation to bring the spaces between adjoining bricks 51 and 52 into register with the face of an abutting brick 53 so that there is no direct passage from the inside to the outside of wall 12.

This arrangement permits the bricks extending in one direction to be spaced from the bricks extending in another direction, and the space thus provided is staggered or stepped in form. This space is filled with any suitable refractory insulation which possesses yieldable properties, such as asbestos for example.

It will be apparent that the foregoing expansion joint will accommodate any expansive movement of the respective stretches of wall 12, and at the same time will effectively prevent escape of the heated gases inside wall 12 into the air space 29 exteriorly of the same.

It will be noted that in all the foregoing constructions, the fire wall 12 is free to move in a lengthwise and up-and-down direction within any range influenced by expansion due to the temperatures to which it is subjected, and at the same time the said wall is constantly maintained at a fixed distance from the cover wall.

Likewise, where necessary, provision is made to accommodate expansion of the cover wall. The anchor portion of the fastening element is 75

so devised that its entire surface may be constantly subjected to the cooling influence of circulating air currents.

The walls of the present invention are simply and easily constructed, and are durable when assembled. The fastening devices are so easily installed that they may be set in place without occasioning loss of time, so that the labor cost of erecting such walls is not appreciably greater than it would be if brick construction were employed throughout.

The tiles and castings are constructed from comparatively inexpensive materials and do not add appreciably to material cost. The fastenings utilize essential elements of the wall construction such as corner columns 14 and supporting columns 31.

Repairs and replacements are readily effected, and one stretch of the wall can be removed and repaired, if necessary, without disturbing the remainder of the wall.

The various materials, shapes and sizes designated throughout the description as preferable are not essential and may be varied in many respects while retaining the essential features of the invention.

Likewise, the arrangements of brick courses and location of fastenings are only illustrative of what may be done, as it will be apparent that each construction will require certain individual treatments.

Changes and modifications may be availed of within the spirit and scope of the invention as defined in the hereunto appended claims.

What I claim and desire to secure by Letters Patent is:

1. The combination with a fire-wall having a plate anchored therein with an edge of the same projecting beyond the wall, of a second wall in spaced relation thereto, a cantilever arch having a slot at one end to admit the projecting portion of the plate, a support for the second wall, and means on the arch engaging the support for maintaining the said walls in substantially uniform spaced relation.

2. In wall construction of the character described, the combination with a tile having a hollowed portion comprising a relatively narrow entrance and an enlarged portion beyond the entrance, of an anchor-element comprising an enlarged body fitted in the enlarged portion of the recess and a narrow neck on the body extending thru the entrance, the body and neck being channeled to admit a circulation of air across their surfaces.

3. The combination with a fire wall, having a plate anchored therein with a portion of the same projecting beyond the fire wall and slotted, of a relatively stationary wall in spaced relation thereto, a slotted beam in the latter wall, and a tie-plate embedded in said stationary wall with a hooked end extending through the slot in the beam and having a tongue at its projected end extending through the slot in the plate.

4. The combination with a fire wall, having a plate anchored therein with a portion of the same projecting beyond the fire wall and slotted, of a relatively stationary wall in spaced relation thereto, a slotted beam in the latter wall, and a tie-

plate embedded in said stationary wall with an upturned end extending through the slot in the beam and having a tongue at its projected end extending through the slot in the plate.

5. In fire wall construction, a tile in a fire wall, having a T-shaped recess, an anchor wall spaced from the fire wall, a headed wall-tie anchored in the recess and projecting therefrom, and means secured to the anchor wall slidably connected for vertical movement with said projecting portion.

6. In fire wall construction, a tile in a fire wall having a T-shaped recess, an anchor wall spaced from the fire wall, a headed wall-tie anchored in the recess and projecting therefrom, and means secured to the anchor wall slidably connected for vertical movement with said projecting portion, there being a channel extending from the recess to the exterior of the wall for the circulation of air across an embedded surface of the tie.

7. In fire wall construction, an anchor wall spaced from a fire wall, a wall-tie anchored in the fire wall and projecting therefrom, and an anchor member embedded in the anchor wall with a side thereof bearing against said wall, the anchor member being interconnected with the projection of the wall-tie.

8. In fire wall construction, an anchor wall spaced from the fire wall, a wall-tie anchored in the fire wall and projecting therefrom, an angle-iron anchored in the anchor wall with a side thereof bearing against the wall, and a link connecting the projection of the tie to the angle-iron.

9. In fire wall construction, an anchor wall spaced from a fire wall, a wall-tie anchored in the fire wall and projecting therefrom, an angle-iron anchor on the outer face of the anchor wall and having a side embedded in the wall, a link connecting the projection of the tie to the angle-iron, a vertical structural member adjacent the outer surface of the anchor wall, and a clip on the angle-iron overlapping the member for vertical movement therealong, and to prevent separation of the angle-iron from the member.

10. In a fire wall, a recessed tile, and a wall-tie anchored in the recess and projecting therefrom, there being a passage from the recess to the exterior of the wall along a surface of the tie for circulating air across the same.

11. In a fire wall, a recessed tile in a fire wall, a channeled and headed wall-tie anchored in the recess and projecting therefrom, an anchor wall spaced from the fire wall, and a hooked element connecting the anchor wall with the tie, there being a transverse slot in the projected portion of the tie for the reception of the hook of the element to permit limited relative horizontal movement between the walls.

12. The combination with a fire wall, of a wall-tie anchored therein and projecting therefrom, having a transverse slot in the projected portion, an anchor wall spaced from the fire wall, and an element connected with the anchor wall having a projection inserted into the slot to loosely tie the walls in spaced relation.
